UNITED STATES PATENT OFFICE

161,958

COMBINATION FLASHLIGHT AND FLASHER
LIGHT

Curt E. Nyberg, Chicago, Ill.

Application May 9, 1950, Serial No. 9,831

Term of patent 14 years

(Cl. D48—24)

To all whom it may concern:

Be it known that I, Curt E. Nyberg, a citizen of the United States, residing at Chicago, county of Cook and State of Illinois, have invented a new, original, and ornamental Design for a Combination Flashlight and Flasher Light, of which the following is a specification, reference being had to the accompanying drawing, forming a part hereof, in which:

Figure 1 is a perspective view of a combination flashlight and flasher light showing my new design; Fig. 2 is a top plan view; Fig. 3 is a front view in elevation; Fig. 4 is a side view in elevation; Fig. 5 is a rear view in elevation; and Fig. 6 is a bottom plan view.

I claim:

The ornamental design for a combination flashlight and flasher light, as shown.

CURT E. NYBERG,
